STRAP FITTING PLATE

Fred R. Cutler, Kansas City, Mo., and Carl R. Peters, Salina, Kans., assignors to American Optical Company, Southbridge, Mass., a voluntary association of Massachusetts

Application July 14, 1937, Serial No. 153,600

2 Claims. (Cl. 33—200)

This invention relates to gauging devices and has particular reference to new and improved means and method of fitting lens straps to lenses.

5 One of the principal objects of the invention is to provide new and improved means and method of fitting lens straps to lenses whereby the straps may be easily and accurately fitted.

Another object of the invention is to provide 10 new and improved means and method of fitting lens straps to lenses, whereby the straps may be bent over a member whose thickness is less than the lens thickness, to allow for the after-working or setting of the strap material.

15 Another object is to provide means and method of fitting lens straps to lenses whereby the operation of gauging the lens thickness and of forming the lens strap to the proper shape, may be performed with a single gauge plate.

20 Another object is to provide means for fitting lens straps to lenses whereby the gauge plate will be of such a shape as to make the fitting simpler and more accurate.

Another object is to provide means for fitting 25 lens straps to lenses, whereby the same gauging article may contain lens thickness gauging members and strap forming and fitting members in designated inter-relation.

Another object is to provide means for fitting 30 lens straps to lenses, whereby the gauging member is provided with means for attaching it to a fixed holder.

Another object is to provide means for fitting lens straps to lenses having a body portion which 35 is tapered to provide a peripheral edge having a varying thickness throughout the contour of the body portion and having a series of openings located at varying selected points on said body portion, said openings being so positioned and directed with respect to the dimensional characteristics of said body portion as to effectively 40 simulate the position of the strap attaching holes of a lens in accordance with a standard set up in the common practice of the art.

45 Still another object of the invention is to provide new and improved means for fitting lens straps to lenses whereby the gauging member is provided with means for sizing and for obtaining an effective trial fit of the strap on the lens.

50 Other objects and advantages of the invention will become apparent from the following description taken in connection with the accompanying drawing, and it will be apparent that many changes may be made in the details of construction, arrangement of parts and methods

shown and described, without departing from the spirit of the invention as expressed in the accompanying claims. We, therefore, do not wish to be limited to exact details of construction, arrangement of parts and method shown and described, as the preferred form only has been given by the way of illustration.

5 Referring to the drawing:

Fig. I is a plan view of the concave side of the gauging device embodying the invention;

10 Fig. II is a sectional view taken on line II—II of Fig. I;

Fig. III is a sectional view taken on line III—III of Fig. I; and

15 Fig. IV is a fragmentary sectional view showing a lens strap attached to a lens.

The fitting of lens straps to lenses has been a very difficult and delicate procedure, calling for the services of highly skilled and experienced operators. In order to provide an aperture between the strap ears which will properly contain the lens, the ears must be bent beyond the point at which the aperture is equal to the lens thickness, to a point from which the after-working of the metal will spring the ears apart enough 20 so that the aperture provided by the final set of the metal will be equal to, or a trifle less than the thickness of the lens.

25 The trial and error method used in the past has been far from satisfactory, because it was 30 not only difficult but inaccurate. The strap may have a seemingly good fit at the time of assembly, but actually the fitting may be too tight, and thus cause a strain in the lens which may lead to its breakage or may be too loose and fail 35 to properly support the lens. In the case of curved or meniscus lenses, the difficulty was even more pronounced due to the angle at which the ears of the straps must be placed to follow the contour of the surface of the lens. In the procedure of fitting lens straps, the operation of gauging the lens thickness and that of bending the strap ears to produce the desired aperture between the ears has in most instances in the past been distinctly separate, and there has been 40 45 no known single device having definite means for determining the amount of aperture between the ears of the strap and also having means correlated with the first means to properly provide the strap with said aperture.

50 Referring to the drawing, the present invention allows for many advantages over the usual method. It provides a gauge plate which has a body portion 40, circular in design, cupped, as shown in Figs. II and III, to form meniscus con- 55

tours with approximately a 6.00 base curve, and having substantially a curved wedge or prism taper shape. Obviously the curve may be other than a 6.00 base but this is selected because it covers the greatest range of lens shapes now in use. The body portion 10 has a central opening 11 and a threaded portion 12 in said opening whereby the gauge plates may be screwed to a holder to facilitate its handling. The gauge plate may be used without a holder if so desired. On one side of the body portion 10, as shown in Fig. I, the periphery has a plurality of gauge slots 13 of various widths for gauging the thickness of the lens to which the strap is to be fitted as shown at 14, accomplishing the first step of the method of fitting lens straps to lenses.

On the other side of the body portion 10 is a plurality of spaced gauge holes 15. As shown in Fig. II the strap ears are first placed over the plate adjacent one of the said gauge holes as in position 18. Then the ears are pressed together over the body portion 10, as shown at 19. An aligning tool 17 is then used to line up the strap ear apertures with the gauge hole. This positioning and lining up provides an effective trial fit of the strap as when in position on the lens. Different curves of lenses require slightly different positions of the strap ear attachment opening with respect to the length of said ear. This position is determined by the above mentioned trial fit and is arrived at by so bending the strap ear as to adjust it the amount required to bring the strap and plate apertures into alignment.

Each of said gauge holes 15 is definitely related to one of the gauge slots 13 by the designations indicated at 20 and 21 so that the proper hole which is to be used is determined by the gauge slot in which the edge of the lens fits during the thickness gauging operation.

The gauge holes 15 are positioned on and through the gauge plate 10 in a very definite relation to the position of strap attaching holes on and through lenses in the common practice of the art. That is, each of said gauge holes is positioned at a distance from the peripheral edge of the body portion 10 equal to that which is commonly set up as a standard between the edge and the strap attached hole of a lens. Also, as illustrated in Fig. II, and in keeping with the common practice in drilling lens strap connecting holes in lenses, the opening 15 is so formed that its longitudinal axis 22 is normal to a line tangent with the surface of the plate at the location at which the said opening is formed in said plate.

The axis 22 then is at an angle 24 with the plane of the plate periphery as indicated by line 23, said angle being substantially equal to a similar angle between the corresponding axis and plane of a lens to which the lens strap is to be attached.

Ophthalmic lenses of today are commonly of meniscus shape and it is common practice in the rimless lens art to maintain the edge thickness as thin as is practical. However, in order to meet different prescriptive requirements, this edge thickness varies. This is one reason why this invention is important, since it provides the means whereby an accurate and positive adjusting and sizing of the strap and aligning of the connecting openings may be obtained so that the strap may be accurately fitted on a lens of a particular thickness and shape and with the standard placement of strap attaching hole.

It is usual in the art of edging ophthalmic

lenses to so form the peripheral edge of the lens that its intersection with any plane containing the line which is the physical axis of the lens after cutting, will be parallel with said axis.

Each slot 13 is numbered, as at 20, and has a hole 15 which is correspondingly numbered, as at 21, and these holes 15 are so constructed and arranged adjacent the peripheral edge of the gauge plate that the taper at each location will provide the desired thickness for the forming of 10 a strap to fit a lens of a thickness established by the corresponding gauge slot.

The thickness of the gauge plate 10 at any of the holes 21 is a little less than the width of the correspondingly numbered slots. This is made possible by the curved wedge or prism taper shape which is designed with a view to providing a plurality of plate thicknesses. The amount of the difference between the above mentioned thickness and width is determined by the after-working factor of the material used in the strap, and must be carefully calculated and taken into consideration in the designing of the gauge plate.

The strap 16 is then positioned and assembled with a lens 14 as illustrated in Fig. IV.

Thus it may be seen that the trial and error method of fitting lens straps to lenses has been discarded, and an easy and accurate method provided whereby the lens is first gauged for thickness, the strap then positioned over the gauge plate at the proper hole for forming and for an effective trial fit, and then positioned on and assembled to a lens.

The strap ears 19 and 23 are bent over the gauge plate, making the aperture between them of a distance slightly less than that of the width of the corresponding slot, enough so that the afterworking of the metal in the straps will spring the ears apart just enough to make a good fit on a lens of the thickness indicated by the gauge slot 40 used. At the same time, when the strap ears are bent over the meniscus shaped gauge plate, they are formed to an angle and curve which will permit the strap to be readily attached to the lens.

The relation between the slots and holes in the gauge plate makes possible the obtaining of a quick and accurate fit of the strap ears to the lens surfaces, and obviates the danger of loose fitting parts or strain and cracking of lenses.

From the foregoing description it will be seen that a particular advantage of this invention is that it provides a device with which all the necessary preliminary operations may be performed prior to securing the strap to the lens, that is, the bending and fitting of the strap to the gauge plate at a position established by the corresponding lens thickness gauge slot and the aligning of the opening in the strap ears with the adjacent hole in the gauge plate which corresponds as to its position with the hole drilled in the lens to receive the strap.

Having described our invention, we claim:

1. A gauge member for gauging and fitting a lens strap to a lens prior to assembly, comprising a body portion cupped to a controlled curvature simulating a standard base curvature of a commercial ophthalmic lens, and having a continuous curved contour edge portion which is tapered to provide varying thicknesses along said edge portion, with the thickness of the said body portion, at designated locations being of a controlled amount less than the edge thickness of a commercial ophthalmic lens of a standard type to which the lens strap is to be fitted, whereby portions of the lens strap overlying the side surfaces of the

gauge member may be pressed until the distance between said lens strap portions is less than the edge thickness of the lens, by an amount such that upon release of said pressure, the said strap portions will inherently separate until the distance between them is substantially equal to the edge thickness of the lens to which said strap is to be attached and the said overlying portions will be shaped to the cupped curvature of said gauge member and similarly substantially to the cupped curvature of the lens.

2. A gauge member, for gauging and fitting a lens strap having perforated strap ears to a lens having an attaching opening therein prior to assembly, comprising a body portion cupped to a controlled curvature simulating a standard base curve of a commercial ophthalmic lens, and having a continuous curved contour edge portion which is tapered to provide varying thicknesses along said edge portion, said body portion having a plurality of openings therein of substantially the same size and spaced inwardly of its contour

edge amounts similar to the distance of the perforation in the lens from the adjacent edge of said lens with the thickness of said body portion at the location of each of said openings being less than the edge thickness of a commercial ophthalmic lens to which the lens strap is to be fitted by an amount sufficient to compensate for the tendency of said material of the strap ears to spring outwardly after being fitted and pressed over the opposed sides of said body portion at a location on said body portion selected according to the particular edge thickness of the lens to which the strap is to be fitted so that after said outward springing the space between the strap ears will be substantially equal to that of the thickness of the lens with the adjacent opening in said gauge plate providing means for aligning the openings in the strap ears with the strap fitted to said plate prior to securing the lens strap to the lens.
